Application February 7, 1944, Serial No. 521,315

5 Claims. (Cl. 178—17)

The present invention relates to feeding devices and more particularly to strip advancing mechanism operable according to a rectilinear action.

The principal object of the invention is to provide a more efficient means for maintaining strip feeding instrumentalities in effective cooperative relationship.

Another object of the invention is to provide a rectilinear feed mechanism wherein the operating elements are readily accessible for adjustment.

A further object of the invention is to provide a more durable structure capable of producing a rectilinear movement in the strip advancing instrumentalities of a record strip sensing unit.

The invention is described herein as embodied in a telegraph transmitter of the type disclosed in U. S. Patent No. 2,262,012, issued November 11, 1941, to R. A. Lake. The tape feeding mechanism according to the present invention introduces an adjustment by means of which the feeding motion of the pins which engage the feed holes in the tape can be varied over a wide range so that manufacturing variations can be cancelled out. Also, so that the feeding stroke can be adjusted to match the spacing of the feed holes in the tape as determined by the adjustment of the star wheel detent of the punch block.

A more comprehensive understanding of the invention may be had from the following description taken in conjunction with the accompanying drawings, wherein:

Fig. 1 is a longitudinal sectional view of a combination perforator and transmitter embodying the present invention;

Fig. 2 is another view of a part of the structure disclosed in Fig. 1, but showing the sensing unit displaced from the perforator;

Fig. 3 is a plan view of the tape sensing portion of the device according to the present invention;

Fig. 4 is a sectional view taken substantially on line 4—4 of Fig. 1; and

Figs. 5, 6, 7, and 8 illustrate certain operational positions of the rectilinear feed mechanism through which the perforated strip is advanced.

Briefly, the structure of the afore-mentioned Lake patent, which exemplifies a device to which the present invention is adapted, may be considered as including three principal units; namely, a tape perforator 11, a tape sensing unit 12, and a transmitting unit 13. Each of the several units is mounted on a base casting 14.

Perforator 11 comprises a set of punches 15 movable through openings in upper and lower

die plates 16 and 17, and which cooperate with a die plate 18. The plates 16 and 18 are spaced apart to form a tape guide, and the punches 15 are selectively operated by an actuating member or punch hammer 19 under the control of interponents 21, corresponding in number to the number of punches 15. The hammer 19 is arranged to oscillate about a pivot 22 and is operated by an arm 23 pivoted to one end of a lever 10 24 which is pivoted on a pivot shaft (not shown) journaled in a suitable bracket mounted on the base casting 14. Lever 24 carries at its opposite end a cam roller (not shown) which cooperates with a cam (not shown) to operate the hammer 15 cyclically and effect its operation and, therefore, the operation of the punch pins 15.

Also mounted on lever 24 opposite to arm 23 is a second arm 25 which has an elongated pin 26 in alignment with a feed punch pin 27. Punch pin 27 is partially enclosed in a housing 28 which conceals a spring 29 arranged to subject punch 27 to spring tension and restore it to its normal position. Punch 27 is guided at its upper and lower extremities by guide plates, and cooperates with a die plate 31 which is separated from the upper punch guide plate to form a tape guide opening for the tape 32. Punch 27 serves to apply to tape 32, the feed holes in advance of the application of the code perforations by code punches 15. It is thus seen that for each operation of lever 24, the hammer 19 will be oscillated about its pivot 22, and the feed hole punch 27 will be moved upwardly by pin 26 which extends through an aperture in hammer 19 to cause the perforation of the feed hole, and will be restored to the position shown in Fig. 1 by spring 29 following the restoration of lever 24 to its position shown in Fig. 1.

The interponent or permutation elements 21 are movable back and forth over the face of hammer 19 and are adapted to be positioned in different combinations to place the outer ends thereof, either in operative positions beneath the corresponding punches 15 or in inoperative positions out of alignment with punches 15.

The free end of hammer 19 is upturned, which portion is slotted to form channels or combs for the forward end of each of the interponents 21. Upon each permutative setting of the interponent 21, lever 24 is oscillated and hammer 19 is moved about its pivot 22 to produce a row of perforations in tape 32 through the actuations of punches 15 corresponding to the setting of the interponents 21. Also, upon the operation of arm 24, elongated pin 26 will be actuated, and

a feed hole punch 27 will be operated to perforate the feed hole in the tape 32 in advance of the perforations in the row of code perforations.

The withdrawal of the feed hole punch 27 is achieved by spring 29, whereas the withdrawal of the code punches is accomplished by a stripper bail 33 which is pivoted at 35 and which has secured thereto one end of a retractile spring 34, but, as disclosed, the punch pins 15 are each provided with a shoulder which cooperates with the lower surface of spring actuated stripper bail 33 so that when the punches 15 are raised, the stripper bail 33 will be moved about its pivot 35 against the action of spring 34 and without any binding action on the punches 15. When hammer 19 is returned to the position shown in Fig. 1, spring 34 is effective to withdraw the actuated code punches 15 and restore them to their normal unactuated position.

As previously described, for each operation of lever 24, punch 27 is operated to form a feed hole in the tape which is thereby adapted to be engaged by the feed pins or teeth of a feed roller 36. The latter is provided with ratchet teeth 38 (Fig. 2) to be engaged by a feed pawl 37 which is pivotally attached to the hammer 19 and which is thus reciprocated on each operation of said hammer, as described more fully in the aforementioned Lake patent. Formed on the outside of the perforator frame and secured to an extension of feed roller 36 is a plate 39 provided with a cam portion 41 arranged to cooperate with an arm 42 formed on the feed pawl 37. Plate 39 is also provided with an arm 43 which cooperates with a slot formed in a member 44 which is capable of being depressed to cause the rotation of plate 39 and through the coaction of portion 41 and extension 42 the withdrawal of feed pawl 37 from cooperation with the teeth of the ratchet 38. The feed roller 36 is thus free to be rotated in an opposite direction to present a previously perforated row of perforations in alignment with the code punches 15. To effect the reverse movement of the tape 32, a spring tensioned lever 45 pivoted on the member 44 cooperates with the star wheel 46 to back space the feed roller 36 and, in turn, back space the tape 32.

A spring 47 connected to the lower extremity of the feed pawl 37 serves to hold the feed pawl in engagement with the ratchet teeth 38 of the feed roller 36, and also normally holds the hammer 19 against the adjustable sleeve 48. When hammer 19 is moved in a clockwise direction by the action of lever 24, the spring 47 is extended. Consequently, when the rotation of lever 24 is reversed, the energy stored in spring 47 is released and the hammer 19 is restored to the position shown in Fig. 2. Feed pawl 37 will be actuated downwardly, and in being so moved, will rotate the feed drum 36 to advance the tape 32 to present a succeeding area thereof in alignment with code punches 15. It is thus seen that upon each operation of hammer 19, feed drum 36 will be rotated and the tape 32 will be advanced step by step.

The interponents 21 are set in different combinations by a plurality of key levers 51 suitably mounted on a pivot rod (not shown) but normally upheld in raised position by individual springs, the levers being provided at their forward end with keytops (not shown).

Beneath the key levers 51 extend a number of code bars 52 and 53, and since in the form shown there are five interponents 21, a corresponding number of pairs of code bars are em-

ployed. Each pair comprises a bar 52 and 53, and each code bar is supported adjacent to each end by a rock arm 54, as fully described in the afore-mentioned Lake patent. Each pair of rock arms 54 is pivoted to a longitudinally movable permutation bar 55. In the form disclosed, each bar 55 is connected to its individual lever 56, which is pivotally mounted on shaft 57 and which at the upper end is connected to their interponents 21; that is, intermediate each bar 55 and its companion interponent 21 is a lever 56 so that for each movement of bar 55 corresponding movement is imparted to interponent 21. Cooperating with the upper end of levers 56 which are beveled is a roller 58 secured to a U-shaped member 60 pivoted on a rod 49 and urged into cooperation with the beveled end of each of the levers 56 by a spring 50. Rod 58 serves as a detent member for levers 56.

20 Each of the key levers 51, which extend across the code bars 52 and 53, is arranged, when operated, to engage and depress one of the code bars of each pair and thereby set the same, and the permutation bars 55 and interponents 21 in a characteristic combination. Correspondingly, the punches 15 will be operated in the same characteristic combination upon the operation of hammer 19 through lever 24.

25 For effecting the operation of the punches 15, including the interponents 21, each key lever 51 is arranged to depress a universal bar (not shown) which controls the punch mechanism, as shown in Fig. 5 of the afore-mentioned Lake patent, and consequently, reference is made to 30 such patent for a full and complete understanding of the construction of the release mechanism which is operated by the universal bar upon the depression of any of the key levers 51.

35 The sensing unit 12, as shown in Figs. 3 and 4, includes two side members 61 and 62. Side member 61, as shown in Fig. 4, extends vertically and is provided at the upper end with a horizontal portion 63, and a reverted or depending portion 64. Member 62 is provided with a vertical portion 67 which is disposed adjacent the portion 64 and is spaced therefrom by a spacer bar 65. Member 62 is also provided with a horizontal portion 69 in the same plane with portion 63 of member 61. Portions 64 and 67 of members 61 and 62, respectively, are welded or riveted together to form a rigid framework; and this framework is pivotally mounted on brackets 68 by means of pilot screws 66. Mounted on horizontal portions 63 and 69 is a tape guide plate 59 having a tape groove 60. Cooperating with said tape groove 60 to suitably guide and retain the tape is a cover plate 70 which is appropriately hinged to plate 59 at 78. A spring means 79 is provided for latching cover plate 70.

40 The sensing unit, as disclosed in Figs. 1 and 2, normally abuts the plates 16 and 18 of the perforator and has the entrance end of its tape channel in alignment with the exit end of the tape channel of the perforator.

45 As viewed in Fig. 3, plate 59 is provided with a plurality of apertures 71 to receive the reduced portion or end of a corresponding series of sensing pins 76; that is, there is a sensing pin 76 individual to each of the code apertures adjacent to the edge of plate 59. Inasmuch as there are five code punches 15, there will be a corresponding number of sensing fingers 76, for example, there will be a sensing finger or pin 76 for each of the possible code perforations appearing in a transverse row of perforations.

The separation between the code punches 15 and the apertures 70 in plate 59 when the plate 59 abuts the plates 16 and 18 corresponds to the normal spacing between successive transverse rows of perforations in tape 32. Usually, the transverse rows of perforations in tape 32 are one-tenth of an inch apart, and therefore, the punches 15 and the apertures in plate 59 are correspondingly separated.

Intermediate the portions 64 and 67 of the frame members 61 and 62 and in the space determined by the spacer 65 is a slidably movable member 77 which carries on its upper extremity a plurality of tape feed pins 81. Pins 81 (in the present embodiment) are so spaced as to engage four successive feed holes in the tape 32. The purpose of providing feed pins for simultaneously engaging four feed holes in the tape is to minimize the possibility of the feed perforations becoming mutilated.

The rectilinear feed means, according to the present invention, is comparable in action to that disclosed in the afore-mentioned R. A. Lake patent, but instead of the pin and cam slot arrangement of the latter patent, a rectilinear feed means is provided which comprises a movable wedging member, a fixed member having a wedging surface, and a movable tape feed pin carrying member. The tape feed pin carrying member also has a wedging surface thereon which, together with the wedging surface of said fixed member, cooperates with the reciprocable movement of the wedging member, which is effective on both of said wedging surfaces simultaneously, to produce in combination with the reciprocable movement of said feed pin carrying member a rectilinear movement of the tape feed pins.

Having reference to Fig. 1, a pin or wedging element 85 (which is comparable to pin 131 of the structure of said Lake patent) is carried on the lever 86 (comparable to a lever 132 of the Lake patent) and is reciprocable vertically by a cam 87, Figs. 5 to 8 (similar to cam 205 of the Lake structure). The pin 85 cooperates with surface 88 of spacer 65. Arm 77 is reciprocated vertically by means of a cam 89 (similar to a cam 207 of the Lake structure). Of course, the peripheral contours of the cams for operating the arm 77 and pin 85 are so chosen as to give the proper rectilinear action.

The member or spacer 65 has two operating surfaces 88 and 91. In addition, member 65 functions to space the two portions 64 and 67 of the frame apart to form a guide for the arm 77. The surface 91 of spacer 65 cooperates with the right-hand upper edge of arm 77 to form the right-hand limit stop for feed pin arm 77. Arm 77 is biased toward this stop surface 91 at all times by springs 92, Figs. 2 and 5. Springs 92 are extended between portions 94 struck from the frame portions 63 and 69 and spring posts 90 on each side of the feed pin arm 77. The operating surface 88 of the spacer 65 and edge 96 of the tape feed operating arm 77 cooperate with the pin 85 which reciprocates vertically during the tape feeding operation, as will presently appear. The upper left-hand edge of the tape feed arm 77 indicated at 93 cooperates with an adjustable stop 95 as the pin 85 on the arm 86 is reciprocated downwardly, as will presently appear.

As will be described hereinafter, arms 77 and 86 are operated in timed relation with each other. Arm 86 is drawn downwardly and when so drawn and due to the particular interrelation between

the surfaces 88 and 96, member 77 will be moved to the left as viewed in Fig. 1, and relative movement between the sensing unit 12 and the tape 32 will be effected. Member 77 then is moved downwardly to withdraw the tape feed pins 81 from engagement with the feed perforations in the tape 32. As arm 77 is thus moved downwardly, arm 86 is also moved downwardly simultaneously an additional amount to maintain lever 77 against stop 95, thereby insuring the downward movement or withdrawal of the tape feed pins in a straight line. Following this action, arm 86 is moved upwardly and due to the cooperation between surfaces 88 and 96 and springs 92, member 77 is moved to the right to engage the stop surface 91. The member 77 is thereafter elevated to cause the pins 81 to engage other feed perforations in the tape 32 to achieve, on a subsequent cycle, relative movement between the sensing unit 12 and the perforated tape 32.

Secured to the side brackets 68 are L-shaped members 101, and extending between the L-shaped members 101 is a pivot shaft 102 on which is mounted a plurality of bell crank levers 103. These bell crank levers are individual to the sensing fingers 76. Each of the sensing fingers 76 is pivotally articulated to the extremity of the horizontal arm of its respective bell crank levers 103 on a center line substantially coincident with the pivots 66. Each of the bell crank levers 103 has a depending portion 104 (Fig. 1) cooperating with a pivotally mounted guide comb 105. Fastened to the vertical arm of each of the bell crank levers 103, at its extremity, is a retractile spring 106, which serves to rotate its respective bell crank in a counterclockwise direction (as viewed in Fig. 1) and to move its associated sensing finger 76 vertically to sense the presence or absence of a perforation in the tape 32. If a perforation is presented opposite a sensing finger 76, said finger moves to its fullest extent upwardly, whereas if there is no perforation in alignment therewith, its movement is correspondingly restricted.

Guide comb 105 is provided at each end thereof with flanges 107 through the instrumentality of which the guide comb 105 is pivotally supported on the shaft 102. Guide comb 105 normally tends to rotate in a clockwise direction about the shaft 102 by a spring 113. As disclosed more fully in the afore-mentioned Lake patent, the rearward flange 107 of the guide comb 105 is adjustably secured to an arm of a T-shaped lever 108 (Fig. 1), also mounted on the shaft 102. Arm 109 on the lever 108 cooperates with a cam 110 (Fig. 3) for cyclically rocking the comb 105 about the pivot shaft 102 for a purpose to be described later. Arm 111 of the lever 108 cooperates with a pin 112 to limit the clockwise movement of the comb 105 against the action of its spring 113 (Fig. 2).

Also mounted on pivot shaft 102 are the bell crank levers for operating the rectilinear feed mechanism of the present invention. For example, rotatably mounted on pivot shaft 102 is a bell crank lever 114 (Figs. 5 to 8) which has one arm 115 pivotally articulated to member 77 of the rectilinear feed mechanism, and another arm 116 cooperating with the cyclically operated cam 89 to effect the vertically reciprocable movement of member 77. Also, pivotally mounted on shaft 102 is a bell crank lever 118 having an arm 119 pivotally connected to member 86 of the rectilinear feed mechanism, and an arm 121 carrying a follower roller 122 which cooperates with the cam 87. Bell crank lever 114 is normally biased coun-

terclockwise by a spring 124 to maintain the cam follower roller on arm 116 in contactual engagement with cam 89. Bell crank lever 118 is normally biased clockwise by a spring 125 to maintain follower roller 122 in contact with the periphery of cam 87.

Secured to the side frame 61 is a pin 126 which cooperates with the insulated upper end of an electrical contact spring 127 which is included in the energizing circuit of a clutch control magnet (not shown) for governing the rotation of the main shaft 128 of the transmitter 13.

Individual to each of the bell crank levers 103 is a bell crank lever 131 pivoted on a shaft 132. Levers 131 are held in proper spaced relation by spacing washers (not shown) on shaft 132, and by a guide comb 133. Each bell crank lever 131 has a hook portion 134 at the upper end of its vertical arm which engages the insulated upper end of a spring contact 135 and each of the latter cooperates with a companion contact spring 136, the pairs of contact springs 135 and 136 being mounted upon but insulated from a supporting bar 137 carried by the base casting 14. Each spring contact 135 tends to engage its companion contact spring 136 and also serves to hold a lug 138 on the horizontal arm of the corresponding bell crank lever 131 into engagement with the surface or periphery of a transmitting cam on a cam drum 139 serving as the signal transmitting cam assembly and forming a part of a cam sleeve 141 (Figs. 3 and 4) on the horizontal shaft 128 and extending over the horizontal arms of the bell crank levers 131. The cam drum 139 is provided with a helical series of notches 142 which, as the cam drum is rotated, successively pass over the vertical lugs 138 of the bell crank levers 131. As the corresponding recess 142 passes over one of the lugs 138, the associated switch contacts 135 and 136 will be closed, provided the horizontal arm of the bell crank lever 131 is not restricted in its movement by the bell crank lever 103, as will presently be described.

Also secured to cam sleeve 141 are cams 87, 89, and 110. Cam 87 operates on cam follower roller 122 carried by the bell crank lever 118 to move arm 119, and, through it, arm 86. Cam 110 operates on arm 109 of the T-shaped lever 108 to rotate the guide comb 105 against the tension of a spring 113 to permit movement of the bell crank levers 103 by the action of springs 106 about the pivot shaft 102 in a counterclockwise direction, as viewed in Fig. 1, and to permit the insertion of the sensing fingers 76 in the perforation of the tape 32 if a perforation is found thereover. During a subsequent portion of the cycle, cam 110 allows spring 113 to actuate the comb 105, through which bell crank levers 103 are rotated about the shaft 102 in a clockwise direction, as viewed in Fig. 1 and thus withdraw the sensing fingers 76 free of the tape 32. As cam 89 rotates, it cooperates with arm 116 of the lever 114 which, through arm 115, reciprocates arm 77 to cause the tape feed pins 81 carried on lever 77 to disengage and engage successively the feed perforations in tape 32.

The particular operation of the rectilinear feed mechanism for advancing the perforated tape 32 through the sensing unit 12, or for causing the sensing unit 12 to move or travel along the perforated tape under predetermined conditions of operation until it abuts the punch block of the perforator, is illustrated in Figs. 5 to 8, inclusive. The indicated figures of the drawings show the rectilinear feed mechanism in its several posi-

tions of operation and will be described in the cyclic order of operation beginning with the normal stop position shown in Fig. 6 and continuing through Figs. 7, 8, and 5. As disclosed in Fig. 6, the mechanism is in its normal or rest position wherein the cams 87 and 89 are in their stop position. Under such conditions, member 77 is in its uppermost and right-hand position, as shown in Fig. 6, wherein the pins 81 are in engagement with the feed holes in the tape. Also, the sensing fingers 76 are in their retracted position.

Upon the release of the cam sleeve, cam 87 rotates therewith and, through cam follower roller 122, lever 118 is rotated clockwise about its pivot 102 to draw the arm 86 downwardly and thus move pin 85 downward between cam surfaces 88 and 96 of members 65 and 77, respectively, until the position shown in Fig. 7 is attained. In response to the downward movement of pin 85 and due to the fact that plate 65 is fixed, member 77 is cammed to the left to the position shown in Fig. 7, against the adjustable stop 95. Thus, because of the engagement of the feed pins 81 with the feed perforations in the tape 32, the tape will be advanced one step or a distance equal to the spacing between adjacent transverse rows of perforations in the tape. During such operation, cam 89 does not impart movement to member 77, but the only motion imparted to member 77 is a counterclockwise motion imparted thereto by pin 85 in cooperation with surfaces 88 and 96.

Following the movement of member 77 to the position shown in Fig. 7, cam 89 becomes effective for moving member 77 through bell crank lever 114, downwardly until the position shown in Fig. 8 is attained. When in the latter position, the sensing fingers 76 hold the tape against movement and retain the tape in its advanced or stepped position. However, before the downward movement of member 77 is started, the sensing fingers 76 are permitted, under the influence of springs 106 and the release of comb 105, to rise and pass through the code perforations in the tape 32, thus functioning to hold the tape against movement. To preclude movement of the tape in the event that no code perforations are found in the tape by the sensing fingers 76, two additional pins 98 and 97 (Fig. 4) are provided which press (under the influence of springs similar to springs 106) against each edge of the tape, a suitable backing being provided above the tape to cooperate with pins 98 and 97. The movement of pins 98 and 97 is also controlled by bail 105. While cam 89 functions, through bell crank 114, to draw arm 77 downwardly, cam 87 also functions, through bell crank 118, to draw arm 86 (and hence pin 85) downwardly an additional amount in order to hold surface 93 of arm 77 against stop 95.

Cam 87, thereafter, is effective to move the arm 86, through its bell crank lever 118, upwardly, thereby moving pin 85, correspondingly, between surfaces 88 and 96, member 77 being biased toward member 65 by spring 92. By such action, and because of the cooperative relation between surfaces 88 and 96, the member 77 will be moved on its pivot to the right until the position shown in Fig. 5 is attained. Then, cam 89, through its bell crank lever 114, moves member 77 vertically to the position shown in Fig. 6. It is noted that in Fig. 5, the tape sensing pins 76 are still in a position to hold the tape against movement. However, in the position shown in Fig. 6, the tape sensing pins 76 are withdrawn

after the tape feed pins have engaged with the tape.

The operations just described in connection with Figs. 5 to 8, inclusive, are repeated in the same cyclic order for each successive cycle of rotation of cam sleeve 141.

If, during the cycle of rotation of cam sleeve 141 just described, there has been no further operation of the key levers 51, the sensing unit 12 remains in abutting relation with the plates 16 and 18 of perforator 11. Pin 126 will have operated contact 127 to open same to break the circuit to the clutch control magnet of the main shaft 128 in the manner shown in the aforementioned Patent No. 2,262,012. However, if during the cycle of rotation of cam sleeve 141, another key lever 51 or other key levers 51 have been depressed, tape 32 will be advanced through the operation of the feed wheel 36, in which case the tape 32 will be drawn through the sensing unit 12 by the action of members 77 and 86 and the transverse rows of perforations in the tape 32 will be sensed successively and the impulses indicative thereof will be transmitted upon the rotation of the sleeve 141.

If the keyboard perforator is operated at a speed considerably faster than the speed of operation of sleeve 141, the sensing unit 12 including the frame members 61 and 62 will be rotated to a position shown in Fig. 2 against a stop pin 151, when a loop of tape as shown in solid lines in Fig. 2 will form between the sensing unit and the plates 16 and 18 of the perforator. As the tape feed pins 81 are operated in a rectilinear fashion, the tape 32 will be advanced through the sensing unit 12 step by step to present the transverse rows of perforations successively to the sensing fingers 76.

If there is a prolonged cessation in the operation of the perforator, while the transmitter 13 is still operating, the loop of tape shown in Fig. 2 will be consumed, and the tape between the sensing unit 12 and the exit channel of the perforator 11 will become taut, as indicated by the dotted line in Fig. 2. Under such conditions, the sensing unit will be advanced in clockwise direction about its pivots 66 along the tape 32. During such movement, the successive rows of perforations will be sensed and the impulses indicative thereof will be transmitted through the rotation of cam sleeve 141.

If, during the afore-mentioned movement of the sensing unit 12 in clockwise direction there is no operation of the perforator 11, the movement of the sensing unit continues until it abuts the plates 16 and 18 of the perforator. When in such position, the last row of perforations in tape 32 will be sensed and the impulses identified therewith will be transmitted. Pin 126 will, in such position, engage the upper end of the contact spring 127 to open the contact to de-energize the electromagnet which controls the main shaft 128.

With the rectilinear feed mechanism herein described, all wearing surfaces (as for example, surfaces 88, 91, 93, and 96) are exposed and are thus readily accessible for machining purposes whereby extreme accuracy of manufacture can be attained. Also, with the adjusting means 95, the feeding motion imparted to the feed pins 81 can be accurately gauged.

Although the invention has been disclosed in connection with a specific embodiment thereof, it is obvious that it may be applied to other forms of apparatus without departing from the spirit

and scope of the present invention as defined by the appended claims.

What is claimed is:

1. In a tape feed device, means for operating a tape feeding mechanism rectilinearly, comprising a fixed member, a reciprocable tape pin carrier member, confronting inclined surfaces upon said fixed member and said tape pin carrier member, a reciprocable wedging member interposed between said inclined surfaces and cooperatively related thereto, cam means for controlling the movements of said tape pin carrier member and said wedging member relatively to produce a rectilinear movement of the tape pins, and means for varying the extent of reciprocity of said tape pin carrier to define the rectilinear movement of the tape pins.
2. In a strip feeding device, a fixed member having a wedging surface, a movable member having a wedging surface, said members disposed in the same plane with said surfaces confronting each other, strip feeding pins carried by said movable member, means for biasing said movable member toward said fixed member, a wedging instrumentality interposed between said members, a cam for controlling said fixed member, a cam for controlling said instrumentality, means cooperating with said cams for actuating both said movable member and said instrumentality reciprocably whereby a rectilinear motion is imparted to said feeding pins, and means for varying the extent of reciprocity of said movable member to define rectilinear movement of the tape pins.
3. Apparatus for imparting step-by-step advancement to a strip having rows of telegraph signal indicia with a feed hole intermediate certain signal indicia comprising a member engageable with the feed holes in said strip, said member having a wedging surface, a fixed element disposed in the same plane with said member and comprising a wedging surface confronting said first recited wedging surface, a wedging instrumentality, means for causing said instrumentality to cooperate with said surfaces for reciprocating said member longitudinally of said strip, means cooperable with said means for causing said member first to be moved free of said strip and then to engage said strip to consummate a rectilinear motion to said member, and means for varying the extent of reciprocatory motion imparted to said member to define the rectilinear motion of said member.
4. In a strip feeding device, elements arranged in the same plane and having confronting wedging surfaces exposed for ready accessibility, strip feeding pins carried by certain of said elements, a wedging instrumentality, resilient means for rendering said wedging surfaces cooperable with said instrumentality, cam means for operating said instrumentality and said certain of said elements to impart reciprocatory movement longitudinally of the strip to said certain of said elements whereby rectilinear motion is imparted to said feeding pins, and means for varying the extent of reciprocatory motion imparted to said certain of said elements by said cam means to define the rectilinear motion of said certain of said elements.
5. A tape sensing device comprising a plurality of members for sensing indicia on a record strip, a movable frame supporting said members, a rectilinear feed means for causing the movement of said frame comprising an element fixed to said frame and an element movable recipro-

cably in said frame, said elements disposed in the same plane and having confronting readily accessible inclined surfaces, means for biasing said movable element toward said fixed element, a wedging member also reciprocably carried in said frame and cooperably engaging said inclined surfaces, cam means for operating said movable

element and said wedging member whereby rectilinear motion is imparted to said feed means, and means for varying the extent of reciprocatory motion of said feed means to define the rectilinear motion of said feed means.
